UNITED STATES PATENT OFFICE.

CLEMENTS A. GREENLEAF, OF INDIANAPOLIS, INDIANA.

TURN-TABLE.

SPECIFICATION forming part of Letters Patent No. 599,934, dated March 1, 1898.

Application filed March 22, 1897. Serial No. 628,589. (No model.)

To all whom it may concern:

Be it known that I, CLEMENTS A. GREENLEAF, a citizen of the United States, and a resident of the city of Indianapolis, in the county of Marion and State of Indiana, have invented certain new and useful Improvements in Turn-Tables for Rail and other Roads, of which the following is a specification.

10 One prominent feature of my invention relates to a novel and advantageous construction for adjusting the pedestal or center-post for a turn-table. It is obvious that the turn-table must have a perfect adjustment to be 15 satisfactory in the operation of turning heavy loads. It is hardly possible to erect the masonry for a turn-table in wet places to exact dimensions, and besides this obstacle in perfectly adjusting the turn-table foundation in 20 the first construction a second obstacle to continued perfect adjustment of the turn-table arises from the fact that the piling or masonry often settles or moves after it is in place. My improved construction for adjustment overcomes these disadvantages and difficulties.

Another feature of my invention relates to novel mechanism for turning the turn-table.

Still another feature of my invention relates 30 to novel means for locking the turn-table when it has reached the desired point in its rotation and where it is to receive its load or to discharge the one theretofore located upon it.

These and other features of my invention 35 will be hereinafter more fully set forth.

The various advantages resulting from the use of these several features, conjointly or otherwise, will be fully specified in the following description.

40 In the accompanying drawings, making part of this specification, and in which similar letters of reference indicate corresponding parts, Figure 1, Sheet 1, shows a vertical central longitudinal section of a turn-table center embodying certain features of my invention. Attention is called to the fact that a vertical central transverse section would only change this drawing, as shown by the dotted lines, showing the length of the cylindrical 45 roll and the projection that it would make on the outside of the cap. Fig. 2, Sheet 1, is a

top view of the turn-table center and the immediate connections thereof and a portion of the adjacent frame connected to the center and upheld by the latter. That half portion 55 of the turn-table which is nearest the spectator has the upper portion removed down so far as the horizontal conical rolls to further illustrate the construction of the turn-table center and its connections. Fig. 3 is a plan 60 of a turn-table, a part thereof (the right-hand end portion) being covered by the upper platform, which carries the track, the remainder of the table being divested of the platform to the better disclose the constructions sought to 65 be presented. Fig. 4 is a vertical section of parts of the base of the turn-table center, showing a modification of a detail of the means for holding the central post to the sole or foundation-plate. 70

I will now proceed to describe my invention in detail.

A indicates the center-post or pedestal, provided at its foot on various sides with horizontal projections A², preferably continuous, 75 and thus forming an annular portion or ring A². The foundation-plate B rests upon a suitable foundation of masonry or of piling, &c., and the plate is securely bolted thereto. If the masonry, piling, &c.—to wit, this lower 80 foundation—moves, the foundation-plate B moves with it. Upon this foundation-plate B rests the center-post A. The correlative portions of this post A and of the foundation-plate B are as follows: The foundation-plate 85 carries at or near its periphery a vertically-projecting rim or flange B². The basal flange A² of the center-post A is in diameter smaller than this projecting rim B². The flange A² of the center-post A is within and inclosed 90 by the rim B², but being of smaller diameter than the latter there is room left (in making the adjustments) to move the center-post to the exact center of the turn-table pit or round-house. There is no particular extent of this 95 adjusting space or room that should be left between the rim B² and the flange A², but the space should be enough to overcome any variation that might occur by settlement or otherwise in the masonry or piling foundations. 100

When the turn-table is to be erected, the foundation-plate B is placed on the subfoun-

dation and anchored thereto. The center-post A is placed on the plate B, the flange A² of the post coming within the rim B² of the plate B. The center-post is then adjusted to 5 a perpendicular by means of the jack-screws C C C, which latter are screwed into the flange A², and as needed to elevate their respective adjacent portions of the flange A² and center-post are screwed through the 10 flange A² and impinge upon the foundation-plate B, lifting the center-post at the point of impingement and in the vicinity thereof. The center-post is then adjusted in a horizontal direction, if necessary, so that the center 15 of it (the center-post) shall be coincident with the center of the turn-table pit or round-house by means of the horizontal adjusting-screws D D D D. Three of such screws would be sufficient, but I have shown four 20 for convenience. These screws are screwed through the rim B², and their inner ends impinge against the center-post, usually against the vertical outer surface of the flange A². By screwing one or another of these screws 25 D the center-post A is moved to the correct position, so that it and the turn-table pit shall be axially coincident. When these perfect vertical and axial adjustments of the turn-table center-post A are obtained, the hold-down-bolts E E E are securely tightened, 30 thereby securing the center-post A to the foundation-plate B and in proper position thereon. These bolts E pass through holes E² in the flange A² and are screwed into the 35 foundation-plate B, as shown. The holes E² are of larger diameter than the bolts and afford the post A opportunity to be moved horizontally, as aforementioned. Washers E³, of a diameter larger than the holes E², embrace 40 their respective bolts and assist the head of the bolt in properly engaging with the upper surface of the flange A² as its screw E is tightened. After the screws E are tightened melted sulfur or other suitable substance 45 is filled into the space between the foundation-plate B and the flange A² of the center-post, making the adjustable center-post secure and ready for the erection of the turn-table thereon. 50 The aforescribed improvements for enabling the center-post to be thus adjusted confer the important advantage of enabling a perfect adjustment of the center-post at the time of the erection of the turn-table, and the 55 further important advantage of being easily adjusted at any time without interfering with the use of the turn-table. This latter adjustment is often required, as the foundation often settles or moves from continued rain or 60 from accident or other causes.

F indicates a piece that makes the lower half of the differential cylindrical joint. This piece F is provided with a concave recess F² in its upper part, substantially as shown, and 65 it also has a circular dowel or cylindrical projection F³ on its lower side that fits the hole in upper housing G and extends down through

said housing G and past the conical rolls H and for a short distance into lower housing J and reaches to within a short distance of the 70 top of the center-post A. This piece F has also a large vertical oil-hole F⁴ through its center. The advantage of the said projection F³ in being thus extended down and continued for a short distance into lower housing J is 75 that such construction prevents any shock that the turn-table may receive from the load passing on or off the same from being communicated to the conical rolls H, for said conical rolls run loose in the housings of this well-known antifriction-bearing. The space F⁵ between the bottom of the part F³ of the piece F and the top of the post A is of about the same height as the annular space H² between the lower housing J and the upper housing G 80 and outside of the rolls H, so that as the conical rolls H wear, as they will do in time, the projection F³ will not come into contact with the projection A³ from the top of post A before the housings G and J will come in contact with each other. 85

The space F⁵ serves to collect the grit or sediment that may pass in with the oil or otherwise and to prevent this grit or sediment from being injected in the antifriction- 90 roller bearing, consisting, as heretofore indicated, of the housings G and J and conical rolls H, as the oil rises from space F⁵, leaving the sediment in bottom of space F⁵ and the oil entering into and distributing itself through 95 said bearing at the space H². The cause of such action of the oil is the pressure in large oil-hole F⁴ when the latter is filled with oil.

K indicates the suspender-bolts.

L indicates vertical rolls provided with 100 housing M.

N indicates the cap, and N² the vertical extensions with which it is provided for the purpose of steadyng it and enabling it at the same time to rotate without friction. These 110 extensions contain the housings M, and therefore the vertical rolls L. These extensions and their rolls are not claimed herein. They and their mode of operation are fully set forth and claimed in the United States Letters Patent No. 563,480, dated July 7, 1896, granted 115 to me for turn-tables.

Z indicates a cylindrical roll lying in the concavity F² of the piece F and entering the concavity N³ of the cap N and supporting the latter. This joint thus formed has, substantially as shown, the differential diameters the same as the differential ball-and-socket joint (set forth in the Letters Patent No. 563,480 granted me) to balance the table to a horizontal plane endwise, but has no side adjustment, as has the differential ball-and-socket joint in said Letters Patent. It will be understood that the side adjustment in the present construction is made at the base of the center-post with the adjusting jack-screws C C C, and when adjusted it is fastened in the horizontal position by the holdown bolts and washers, (marked E E E,) as there is no need 120 125 130

of any side motion to the turn-table platform in turning; but the table should always remain in a horizontal position sidewise and only tip endwise.

5 The advantage of the adjustable center-post is plain. For instance, the turn-table must have perfect adjustment to be satisfactory in turning heavy loads.

R is a reservoir to hold compressed air. 10 R² is a hose-coupling to fill said reservoir from the locomotives.

R³ is a pipe conducting the compressed air from the reservoir to a hollow stop cock or valve, (marked S.)

15 S² is a connection-pipe that connects valve S to two pneumatic hoists, (marked T T.) Said hoists T T operate wire rope T² to pull in either direction. Said wire rope T² is coiled several turns around the turn-table center-post. Said center acts as the drum or fulcrum by which to turn the turn-table around in either direction or to stop the same at any desired point. The hollow stop-cock S receives the compressed air continuously 20 through the conducting-pipe R³ and is operated by the lever V into either hoist T T at will through connecting-pipe S². The openings or port-holes in hollow stop-cock S are so arranged that either or both hoists T T 25 can receive compressed air at the will of the operator of lever V.

W is a bracket bolted onto the side of the turn-table and supports a hollow column W². Said column W² has on the inside suitable 30 boxes to receive vertical shaft W³. Said shaft W³ and hollow column W² are of suitable length, so that the lever V is in easy reach of the engine-runner when he is on the locomotive while on the turn-table. On the lower 35 end of shaft W³ is an arm W⁴, which arm is connected to the valve (hollow stop-cock) S by connection-rod W⁵, so that any movement of lever W² is immediately communicated to valve S.

40 45 X X are two pipes that conduct compressed air, when desired, to cylinder X². Said cylinder X² is provided with a suitable valve—e. g., "Knowles"—to receive and exhaust compressed air at either end of said cylinder X². The locking-bolt X³ has an enlarged end 50 that forms a piston-head in cylinder X², and said locking-bolt is operated in a reciprocating motion at the will of the engine-runner who handles lever V.

55 When the operator has the turn-table about in the position that he wants it to run off the table with the locomotive, he by a slight movement of lever V shoots the locking-bolt into place, where it remains until the table is 60 to be moved around to receive another locomotive. The lever V is then moved so as to admit compressed air into the other end of the Knowles valve, which discharges the compressed air from one end of cylinder X² and admits it into the other end and shoots the locking-bolt X³ back to the place of beginning and leaves the table free to be turned

by hand. The locking-bolt X³ is an additional device to the automatic locks patented by me in my said Letters Patent No. 563,480 70 and is to be used in turning by power at the same time with said automatic locks. The locking-bolt is an additional safeguard required, because the engine-runner is not in a position to see when the turn-table is in exact position to enter the automatic locks.

75 Y is a cross-beam supporting two sheaves; provided with suitable axles Y² Y² to hold wire rope T² in a pulling position to turn the turn-table around or stop the same. The 80 holes that are to be made on the inside of the turn-table-pit wall must have a vertical depth sufficient to allow the table to tip to the bearings on automatic locks described in said Letters Patent No. 563,480; but said holes may fit the locking-bolt laterally. The advantage 85 of this construction and arrangement of said device is that the engineer can take out locomotives at any hour of the night when the yardmen are not about.

90 Referring to my turn-table center, a modification of certain features of my invention consists in substituting wedges B⁶ for the hold-down-bolts E and the laterally-adjusting screws D. In such event the upper inner part of the vertical rim of the foundation-plate B may have an overhanging projection B⁴, having a bevel side or face B⁵. The outer upper edge or projection of the center-post 95 may have beveled spots or faces A³. Each 100 edge B⁶ is inserted between such adjacent faces B⁵ and A³.

105 My invention in turn-table centers is advantageously applicable to gun-turrets and gun-carriages, as well as telescopes on ship-board, for the reason that with it the load always balances to a horizontal plane.

What I claim as new and of my invention, and desire to secure by Letters Patent, is—

110 1. The cylindrical roll Z and the concave in the top or cap N, and the concave in the bed-piece F, these concaves receiving the cylindrical roll, but having the differential diameters, in relation to the diameter of the roll, and forming the differential joint for balancing the table to a horizontal plane in the direction of its length, in combination with the center-post A and the foundation-plate B, and the adjusting jack-screws C, and devices for holding the center-post down to 115 place to the foundation-plate, substantially as and for the purposes specified.

120 2. The cylindrical roll Z and the concave in the top or cap N, and the concave in the bed-piece F, these concaves receiving the cylindrical roll, but having the differential diameters, in relation to the diameter of the roll, and forming the differential joint for balancing the table to a horizontal plane in the direction of its length, in combination with the center-post A and the foundation-plate B, and the adjusting jack-screws C, and the hold-down-screws E, substantially as and for 125 130 the purposes specified.

3. The cylindrical roll Z and the concave in the top or cap N, and the concave in the bed-piece F, these concaves receiving the cylindrical roll, but having the differential diameters, in relation to the diameter of the roll, and forming the differential joint for balancing the table to a horizontal plane in the direction of its length, in combination with the center-post A and the foundation-plate B, and the adjusting jack-screws C, and the

hold-down-screws E, and the horizontal bolts D, the plate having vertical projection for the latter, and the center-post having lateral projection for the screws C and screws E, substantially as and for the purposes specified. 15
